AUTOMATIC TRILL-PRODUCING DEVICE FOR ELECTRONIC MUSICAL INSTRUMENTS

BACKGROUND OF THE INVENTION

This invention relates generally to electronic musical instruments and more particularly to a new automatic trill-producing device for electronic musical instruments.

Generally speaking, the term "trill" means a kind of ornamental sound wherein a principal note and an auxiliary note two scale degrees above the principal note are rapidly alternated or means for obtaining such an ornamental sound.

However, in playing a piano, organ, or an electronic musical instrument, the production of good trill sounds requires a long period of training, and, moreover, there is a limitation to the trilling frequency. Furthermore, no musical instrument capable of automatically producing trills has been proposed.

SUMMARY OF THE INVENTION

Therefore, the primary object of the present invention is to provide a novel organization of an electronic musical instrument having a keyboard, which is capable of automatically producing trill sounds by the mere depressing of two keys between which each trill sound is desired to be alternated.

The above stated and other objects of the present invention can be achieved by a novel organization of the trill-producing device according to the invention which comprises a plurality of switching circuits or tone generators, first and second groups of changeover switches, make-contacts of said first and second group of changeover switches being connected to said switching circuits or tone generators respectively, break-contacts and moving contacts of said first group changeover switches being connected in a "high note priority" arrangement, break-contacts and moving contacts of said second group changeover switches being connected in a "low note priority" arrangement, an automatic changeover switch connected to a control power source or to an amplifier and loud-speaker combination, one switch position of said automatic changeover switch being connected to the moving contact of the highest note changeover switch belonging to the first group, and another switch position of said automatic changeover switch being connected to the moving contact of the lowest note changeover switch belonging to the second group, whereby electric energy from said control power source is alternately conducted to said switching circuits, or the tone signals generated from said tone generators are alternately conveyed to said amplifier and loudspeaker combination.

The nature, principle, and utility of the invention will be more readily apparent from the following detailed description with respect to preferred embodiments of the invention when read in conjunction with the accompanying drawings, in which like parts are designated by like reference numerals.

BRIEF DESCRIPTION OF THE DRAWINGS

FIG. 1 is a block diagram showing an example of a trill device according to the present invention; and

FIGS. 2 and 3 are block diagrams showing other examples of the trill device also according to the present invention.

DETAILED DESCRIPTION

In the present invention, the term "trill" is used with a somewhat expanded meaning, so that the terms "trill," "high note priority," and "low note priority" which are used frequently in this specification will be defined as follows.

Trill: A method of playing wherein two sounds different in scale degrees are rapidly alternated or the result of such playing.

High note priority connection: A mode of connection of changeover switches interlinked with the keyboard of an electronic musical instrument, wherein the changeover switches each having a make-contact (normally opened contact), a break-contact (normally closed contact), and a moving contact are connected sequentially in such a manner that a break-contact of a switch located at the high note side is connected to the moving contact of an adjacent switch located at the low note side of the former switch, and all of the make-contacts of the above-described changeover switches are connected, for instance, respectively to switching circuits and the moving contact of the switch interlinked to the highest note key is connected to an electric source, whereby, when a plurality of switches interlinked respectively with a group of keys are depressed simultaneously, only the make-contact of a switch interlinked with the highest note key in the group is connected to the power source.

Low note priority connection: A mode of connection of the changeover switches that is substituted "Low note" for "High note" in the definition as to the above-mentioned "High note" connection, whereby when a plurality of switches interlinked respectively with a group of keys are depressed simultaneously, only the make-contact of a switch interlinked with the lowest note key in the group is connected to the electric power source.

Referring now to FIG. 1 showing a block diagram of an example of the trill device according to the present invention, a portion of the diagram designated by reference numeral 1 and encircled by a broken line is one of the circuit components of the trill device, one component being provided for each key of the keyboard of a musical instrument to which the trill producing device according to the present invention is applied. Since this circuit component 1 is positioned at the extreme right-hand side, as viewed in FIG. 1, it is assumed that the circuit component 1 corresponds to the key of the highest note in the keyboard and the succeeding circuit components correspond to keys of the subsequent notes descending sequentially from the right to the left.

Each of the circuit components 1 comprises a switching circuit 2 which passes or stops a tone signal when a control terminal is energized from a control power source as in the case of the conventional switching circuit. A tone signal from a tone generator 2a is delivered to an amplifier 10 when each of the switching circuits 2 is closed under energization of the control terminal as described above.

In the circuit components 1, there are also provided with two groups of changeover switches 3 and 4 which are open-or-closed in interlinked relationship with each other and also with the keyboard, and each of the switches 3 and 4 has a make-contact, a break-contact, and a moving contact as described herein before. Furthermore, one group of the changeover switches 3 are connected in "high note priority," and the other group of the transfer switches 4 are connected in "low note priority."

There is also provided an automatic switch 5, one contact of which is connected to the moving contact of a changeover switch 3 corresponding to the lowest note key, and the other contact of which is connected to the moving contact of a changeover switch 4 corresponding to the lowest note key. The moving contact of the automatic switch 5 is connected to a control power source 6 provided for controlling the switching circuits 2. With this arrangement, the automatic switch 5 connects the control power source 6 to the above described moving contact alternately at a frequency of, for instance, 10 Hz which is equivalent to a desired frequency of the trill. The function of the automatic switch 5 may also be realized by employing any of the conventional transferring measures such as an electromagnetic relay or an electronic multivibrator.

It should be noted that the control terminal of the switching circuits 2 are connected to the make-contacts of the changeover switches 3 and 4 interlinked with each other and also with respective keys on the keyboard, and that the moving contact of the changeover switch 3 corresponding to the highest note and the moving contact of the changeover switch 4 corresponding to the lowest note are alternately connected to the control power source 6 through the automatic switch 5.

In FIG. 2 showing another example of the trill device according to the present invention, wherein parts similar to those in the circuit of FIG. 1 are designated by correspondingly like reference numerals, there are additionally provided a plurality of diodes 7 which are connected respectively to the moving contact of the changeover switches 4, and a trill-normal selecting switch 8 which can be operated by an operator of the musical instrument when he desires to render a trill sound. The other terminals of the diodes 7 are commonly connected to one contact of the selecting switch 8, and the other contact of the switch 8 is connected to the moving contact of the automatic switch 5. The normally conducting directions of the diodes 7 are from the transferring arms of the switches 4 toward the commonly connected contact of the selecting switch 8.

The examples of the trill device shown in FIGS. 1 and 2 operate as follows.

In the device of FIG. 1, when two keys corresponding to two notes between which a trill sound is desired are continuously depressed, the control power source 6 is alternately connected to the control terminals of two switching devices 2 in the circuit components 1 corresponding respectively to said two keys on the keyboard, through the changeover switches 3 and 4 connected in "high note priority" and "low note priority" and through the automatic switch 5 which is alternating at the above described frequency.

Thus, in the period when the control power source 6 is connected to the moving contact of the switch 3, the switching device 2 corresponding to the higher note key operates so that a higher tone is delivered, and in the period when the control power source 6 is connected to the moving contact of the switch 4, another switch device 2 corresponding to the lower note key operates so that a lower tone is delivered, whereby when the two tones are alternated at a frequency determined by the automatic switch 5, a desired trill sound is produced from the musical instrument.

Whenever three or more keys are depressed, a trill sound alternating between the highest note and the lowest note out of these depressed keys is obtained, and, when only one key is depressed, the same note is continuously delivered from the musical instrument, and there is no disturbance or trouble of the playing of the musical instrument.

The device shown in FIG. 2 has a provision whereby normal performance and trill performance can be selected from one to the other. When the trill-normal selecting switch 8 is thrown into the indicated position, the control power source 6 is connected to a moving contact of the switch 4 corresponding to a depressed key through a diode 7, and an ordinary performance of the musical instrument can be obtained. Although the direction of the diodes 7 is indicated to be suitable for a control power source 6 having negative polarity, it will be apparent that the conductive direction of the diodes 7 may be reversed if a control power source 6 of positive polarity is desired. Furthermore, although the diodes 7 are indicated to be connected to the switches 4, it will be apparent that the diodes 7 may also be connected to the switches 3 for obtaining similar results.

When the trill-normal selecting switch 8 is thrown into a position opposite to the indicated position, the control power source 6 is connected similarly as in the case of FIG. 1, whereby the trill is rendered as described above. In this case, the commonly connected terminals of the diodes 7 are disconnected from the control power source 6, and the diodes 7 are connected reversely in the circuit passing through the commonly connected terminals of the diodes 7, whereby the existence of the diodes 7 has no influence on the trill-producing operation of this device.

Still another embodiment of the present invention is shown in FIG. 3. In this example, the output terminals of tone genera-

tors 9 are connected to the make-contacts of the changeover switches 3 and 4 interlinked with the keyboard instead of the switching devices 2 as in the previous examples. The changeover switches 3 and 4 interlinked with the keyboard are connected in "high note priority" and "low note priority" respectively, and connected to the automatic switch 5 as described in the two preceding examples. The moving contact of the automatic switch 5 is now connected to an amplifier 10 and a loudspeaker 11, successively.

With this arrangement, the trill is obtained in such a manner that the output tones from the tone generators 9 are transferred alternately by means of the automatic switch 5 and then connected to the amplifier 10 and the loudspeaker 11 for delivering the trill sound. In this case, the operations of the changeover switches 3 and 4 connected in "high note priority" and "low note priority" and also of the automatic switch 5 are quite similar to those in the aforescribed examples.

In all of the above described examples of the trill-producing device according to the present invention, the trill sound can be produced merely by depressing two keys between which the trill sound is desired to be alternated, and the transfer or changeover between trill operation and normal operation of the musical instrument can also be carried out by means of a simple switch.

Although the invention has been described with respect to preferred embodiments thereof, it will be apparent that various modifications, such as the use of tone generators instead of the switching devices in FIG. 2 and an amplifier and loudspeaker combination instead of the control power source of the same drawing, with all of the diodes connected as in the case of FIG. 2, can also be made without departing from the spirit and scope of the present invention.

I claim:

1. An automatic trill-producing device for an electronic musical instrument having a keyboard, comprising a plurality of switching devices for passing-or-stopping tone signals, first and second groups of changeover switches respectively interlinked to keys of the keyboard and connected according to "high note priority" and "low note priority" modes, make contacts of said first and second groups of changeover switches being connected to said switching devices, an automatic switch operable at a predetermined frequency having a contact point connected to a moving contact of a first group changeover switch interlinked with the highest note key and another contact point connected to a moving contact of a second group changeover switch interlinked with the lowest note key, and a control power source connected to said automatic switch.

2. An automatic trill-producing device as set forth in claim 1 wherein a plurality of diodes are further connected respectively to said second group of changeover switches, and a trill-normal selecting switch is provided between said automatic switch and said control power source.

3. An automatic trill-producing device for an electronic musical instrument having a keyboard, comprising a plurality of tone generators, first and second groups of changeover switches respectively interlinked to keys of the keyboard and connected according to "high note priority" and "low note priority" modes, make contacts of said first and second groups of changeover switches being connected to said switching devices, an automatic switch operable at a predetermined frequency having a contacting point connected to a moving contact of a first group changeover switch interlinked with the highest note key and another contact point connected to a moving contact of a second group changeover switch interlinked with the lowest note key, and an amplifier and loudspeaker combination for delivering the trill sound from the trill-producing device.
